US00D947178S

(12) **United States Design Patent** (10) Patent No.: **US D947,178 S**
(45) Date of Patent: **** Mar. 29, 2022**

(54) **PORTABLE TERMINAL**

(71) Applicant: **Soo Hyun Chae**, Seoul (KR)

(72) Inventor: **Soo Hyun Chae**, Seoul (KR)

(**) Term: **15 Years**

(21) Appl. No.: **29/715,117**

(22) Filed: **Nov. 27, 2019**

(30) **Foreign Application Priority Data**

May 31, 2019 (KR) 30-2019-0025908

(51) **LOC (13) Cl.** **14-02**

(52) **U.S. Cl.**

USPC **D14/344**

(58) **Field of Classification Search**

USPC ... D14/126-130, 138, 138 R, 144, 300, 341, D14/344, 358, 388, 485-495, 218; D10/30-39, 40, 41, 46, 70, 79, 98, 106.5, D10/106.6, 106.92, 106.94, 114.6, 123, D10/125-128, 131; D11/1-4, 26, 40-41, D11/93, 94, 78.1, 79, 86; D24/167-169, D24/186-187, 164; D21/324-329 CPC A41D 1/002; A41D 19/0034; G06F 1/08; G06F 1/10; G06F 1/14; G06F 1/1626; G06F 1/1628; G06F 1/163; G06F 1/1635; G06F 1/3203; G06F 1/1613; G06F 2200/1633; G06F 3/0488; G06F 3/0486; G06F 3/044; G06F 3/0412; G06F 3/0416; G06F 1/3215; G06F 2203/04102; G06Q 20/10; G06Q 20/12; G06Q 20/108; G06Q 20/145; H04B 1/3833; H04B 1/385; H04B 1/3888; H04M 1/02; H04M 1/03; H04M 1/04; H04M 1/05; H04M 1/667; H04M 1/6058; Y02B 60/1217; A44C 5/0007; A44C 5/0015; A44C 5/0023; A44C 5/0084

(57) **CLAIM**

The ornamental design for a portable terminal, as shown and described.

DESCRIPTION

FIG. 1 is a perspective view of the portable terminal showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines show portions of the portable terminal that do not form part of the claimed design.

1 Claim, 7 Drawing Sheets
